PORTABLE EVAPORATIVE COOLER

Adam D. Goettl, Albert B. Goettl, and
Edward C. Klotz, Jr., Phoenix, Ariz.

Application November 9, 1956, Serial No. 43,714

Term of patent 14 years

(Cl. D62—4)

The figure is a perspective view of a portable evaporative cooler showing our new design. The side and back not shown are substantially the same in appearance as the side shown wherein the vertical lines represent air inlet louver grills.

We claim:

The ornamental design for a portable evaporative cooler, substantially as shown and described.
